Design U.S. Appl. No. 29/430,427, Applicant: Natashia Ingemarsson-Matzen.

Utility U.S. Appl. No. 14/402,312, Applicant: Jeremy Kenyon.

Primary Examiner — Rhea Shields

(57) **CLAIM**

The ornamental design for a dental plate, as shown and described.

DESCRIPTION

1.1 is a top view my new design for a dental plate;
 1.2 is a top isometric view of 1.1;
 1.3 is a right side view of 1.1;
 1.4 is a front view of 1.1 with the dental plate in a folded and engaged position;
 1.5 is a rear view of 1.1;
 1.6 is a left side view of 1.4;
 1.7 is a left side isometric view of 1.4; and
 1.8 is an enlarged view of a portion of 1.7.
